(57) **CLAIM**

The ornamental design for a robotic development platform, as shown and described.

DESCRIPTION

FIG. 1 is an elevated perspective view of one embodiment of the ornamental design for a robotic development platform showing my new design;

FIG. 2 is a top view thereof;

FIG. 3 is a side view, the other side being a mirror image thereof;

FIG. 4 is a front view thereof;

FIG. 5 is a rear view thereof;

FIG. 6 is a bottom view thereof;

FIG. 7 is an elevated perspective view of another embodiment of the ornamental design for a robotic development platform showing my new design;

FIG. 8 is a top view thereof;

FIG. 9 is a side view, the other side being a mirror image thereof;

FIG. 10 is a front view thereof;

FIG. 11 is a rear view thereof; and,

FIG. 12 is a bottom view thereof.
